METHOD OF FORMING BRAKE DRUMS AND APPARATUS THEREFOR

Joseph E. Batie, Detroit, Mich., assignor to Kelsey-Hayes Wheel Corporation, Detroit, Mich., a corporation of New York

Application November 3, 1930, Serial No. 493,209

4 Claims. (Cl. 29—90)

The invention relates to apparatus for forming brake drums and refers more particularly to apparatus for ironing the brake flanges of drums. One of the objects of the invention is to provide an improved apparatus which effectively irons the brake flange of a drum without marring its surface. Another object is to provide an improved apparatus which effectively irons the brake flange of a drum irrespective of its thickness, which varies within certain limits in production. These and further objects of the invention will be apparent from the following description, taken in connection with the accompanying drawing, in which

15 Figure 1 is a central vertical section of an apparatus illustrating an embodiment of my invention;

Figure 2 is a plan view thereof, with the parts broken away.

20 The apparatus, as illustrated in the present instance, has the base 1 which comprises the table 2 and the legs 3. Mounted upon and secured to the table is the die holder 4 having the base 5 and the circular upright flange 6. 7 is a circular die 25 within the flange 6 and mounted upon and secured to the base 5. This die is engageable with the outer face of the brake flange 8 of the brake drum, which latter, when in place, has its web 9 resting upon and supported by the ring 10 which 30 in turn is mounted upon the base 5.

A circular series of upwardly tapered rolls 11 is engageable with the inner face of the brake flange 8. Each of these rolls is secured to the lower end of a shaft 10", which shaft extends 35 upwardly through and is journaled in a slide 12. Each shaft has at its upper end a head 10' between which and the upper end of the slide there is the anti-friction bearing 13 for supporting the shaft upon the slide. Each slide 12 is 40 slideable in a radially extending guideway 14 formed by a radial slot in the annular flange 15 of the lower section 16 of the carrier 17. Each slide has at its upper and lower ends retaining flanges 18 for preventing disengagement of the shoe 45 from the carrier by a longitudinal movement of the slide relative to the carrier. Each slide is resiliently held in its innermost radial position by a coil spring 19 which extends radially of and is secured in the flange 15 and has its outer end 50 abutting a plug 20 and its inner end abutting a slide.

The carrier 17 has the upper section 21 which is sleeved upon the lower section 16 and is loosely secured thereto by the shouldered bolts 22, 55 there being coil springs 23 under compression

between the upper and lower sections tending normally to separate these sections. The carrier is rotatably supported upon the head 24 of a suitable machine, such as an automatic drill, by means of the circular flanged member 25 which is secured to the head. 26 and 26' are anti-friction bearings for respectively supporting the upper section of the carrier and forcing this section downwardly. 27 and 27' are thrust plates for engaging the bearings 26 and 26' respectively, these plates being encircled by the flanged member 25 and respectively resting thereon and clamped thereby against the head 24.

For the purpose of moving the rolls 11 outwardly to engage the brake flange 8 and to force this brake flange against the die 7, I have provided a plunger 28 which is movable axially of the die and has at its lower end the cam 29 formed with a downwardly tapered circular peripheral face. The tapered rolls are so mounted that the portions of their faces at the time of engagement with the inner face of the brake flange 8 are vertical or parallel to the inner face of the die 7 and the portions of the faces of these rolls at the time of their engagement with the cammed member are inclined to the axis of the plunger, so that downward movement of the plunger cams the rolls radially outward. The plunger is designed to be carried by the rotatable spindle of the machine, such as an automatic drill, and to provide for relative 75 rotation between the plunger and the roll carrier. I have provided the bearing 30 between the shank of the plunger and the lower section 16 of the carrier.

For the purpose of limiting the downward 80 movement of the plunger, I have provided the post 32 which is mounted upon and extends upwardly from the base 5. Threadedly engaging this post is the abutment 33 which is engageable with the head 34 at the lower end of the pin 35. The 85 post, abutment and pin extend within the plunger and the pin is journaled in the shank of the plunger but held from longitudinal disengagement therefrom by means of the set screw 36. 37 is a suitable anti-friction bearing between the 90 head 34 and the ring 38, the upper face of which latter abuts an annular shoulder formed in the plunger. 35' is a bearing between the shank of the pin 35 and the plunger.

To eject the brake drum after its brake flange 105 has been ironed, I have provided the rods 39 which extend upwardly through the table 2 and the base 5 and are engageable at their upper ends with the ring 10. The lower ends of these rods rest upon the support 40 which is connected to 110

the rod 41 rigidly secured to a piston slidable within the cylinder 42 carried by and depending from the table 2 and encircled by the legs 3. Fluid under pressure, such as compressed air, may 5 be used for actuating the ejecting mechanism.

In operation, it will be seen that the rolls 11 will first be lowered to the full extent into the brake drum, after which the plunger is lowered still more to cam the rolls radially outward into 10 engagement with the brake flange of the drum and to carry this brake flange against the die. The plunger is being rotated so that as soon as its cam member comes into contact with the rolls these rolls will be rotated causing the same to 15 travel over the brake flange. As a result, the effective braking surface of this brake flange is effectively ironed regardless of variations in its thickness so that this brake flange will remain circular upon removal of the brake drum from the 20 apparatus. After the ironing operation has been completed, the plunger is first raised and during this initial raising operation the coil springs acting upon the slides supporting the rolls force these slides radially inward to disengage the rolls from 25 the brake flange. After disengagement of the rolls from the brake flange upward movement of the head carries the roll carrier upwardly. By reason of this construction, marring of the inner 30 face of the brake flange by withdrawal of the rolls is avoided so that this inner face is highly finished.

What I claim as my invention is:

1. In apparatus for forming brake drums, the combination with a die for engaging the brake flange of the drum, of a carrier rotatably mounted relative to the die, a plurality of rolls mounted upon the carrier for movement radially thereof into and out of engagement with the brake flange, means for moving the rolls radially into engagement with the flange for expanding the same 35 against the die and also for rotating the rolls around the braking surface of the flange to iron the same, means operable upon completion of the ironing operation to move the rolls away from said flange, and means for subsequently ejecting 40 the brake drum from the die.

2. In apparatus for forming brake drums, the

combination with a support for a brake drum, a die encircling the brake flange of the drum and a rotatable carrier movable toward and away from the drum, of a plurality of rolls projecting beyond the carrier and having shafts journaled in bearings slidably and rockably supported in the carrier for radial movement relative thereto, means for moving the carrier toward the drum for positioning the rolls in operative relation to the brake flange, yieldable means normally urging said rolls radially of the carrier away from the brake flange, and means for camming said rolls into engagement with the brake flange for expanding the same against the die.

3. In apparatus for forming brake drums, the combination with a support for a brake drum, a die encircling the brake flange of the drum and a carrier movable toward and away from the drum, of a plurality of rolls projecting beyond the carrier and having shafts journaled in bearings slidably and rockably supported in the carrier for radial movement relative thereto, means for moving the carrier toward the drum for positioning the rolls in operative relation to the brake flange, and means for moving said rolls radially into engagement with the brake flange for expanding the same against the die.

4. In apparatus for forming brake drums, the combination with a stationary die for engaging the brake flange of the drum, of a carrier mounted for rotation relative to the die and movable toward and away from the drum, a plurality of bearings mounted for sliding and rocking movement within radial slots formed in said carrier, rollers for engaging the brake flange of the drum and having spindles journaled within said bearings, means for moving the carrier toward the drum for positioning the rollers in operative relation to the brake flange, and means for camming said rollers into engagement with the brake flange for expanding the latter against the die and for simultaneously rotating said rollers about their axes.
